CLAIM

The ornamental design for an air purifier, as shown and described.

DESCRIPTION

1. Air purifier

1.1 : Perspective

1.2 : Front

1.3 : Back

1.4 : Left

1.5 : Right

1.6 : Top

1.7 : Bottom

1.8 Cross-section

1.9 Cross-section

The material is synthetic resins and metallic material; The present design is for air purifier that keeps indoor air clean by purifying and discharging inhaled air; Figure 1.8 is a cross-sectional view configured along line A-A' of the front view, illustrating the outer shape excluding the internal shape. Figure 1.9 is a cross-sectional view configured along line B-B' of the front view, illustrating the outer shape excluding the internal shape.
